REEL CARRYING TRAILER

Joseph C. Devine, R.D. 1, Box 206,
Grantville, Pa. 17028

Filed June 11, 1975, Ser. No. 585,848

Term of patent 14 years

Int. Cl. D12—10
U.S. Cl. D12—101

FIG. 1 is a perspective view from the front and one side of a reel carrying trailer showing my new design; and FIG. 2 is a rear perspective view thereof.

I claim:

The ornamental design for a reel carrying trailer, as shown.
